UNITED STATES PATENT OFFICE.

MORRIS H. SIEGEL, OF NEW YORK, N. Y., ASSIGNOR TO BEATRICE SANVILLE, OF NEW YORK, N. Y.

GARMENT BUTTON.

Application filed August 15, 1924. Serial No. 732,194.

To all whom it may concern:

Be it known that I, MORRIS H. SIEGEL, a citizen of the United States, and a resident of New York city, in the county and State 5 of New York, have invented certain new and useful Improvements in a Garment Button, of which the following is a specification.

Among the principal objects which the 10 present invention has in view are: To prevent the detachment of a button from the article of wear with which it is associated in service; to provide a button which may be stationarily secured to the garment with 15 which it is associated in service; and to simplify and cheapen the construction of the invention.

Drawings.

20 Figure 1 is a side view of a collar button, constructed and arranged in accordance with the present invention.

Figure 2 is a vertical section thereof showing in conjunction therewith, a fragment of fabric, the button being stationarily and permanently secured thereto.

Figure 3 is a cross section of the same, the section being taken on the line 3-3 in Figure 2.

30 Figure 4 is a sectional side view of the button shown in Figure 1, the section being taken as on the line 4-4 in Figure 1.

Description.

35 The invention is shown as adapted for use in conjunction with collar buttons such as are provided with the head 9, shank 10, and base 11. In shape and design, the button, in so far as the parts enumerated are 40 concerned, is the same as the usual or customary button. In adapting the button to the needs of the present invention, however, the head 9 is slotted to receive the U-shaped end of a spreading spring retainer 12. The retainer 12 fits over the stem 10 in a manner best shown in Figure 2 of the drawings. It is thereafter held by the head 9 when the same is pressed over the end of the stem 10 in the manufacture of the button.

50 The retainer 12 has clamping feet 13. When not restrained by the ring girdle 14, the feet 13 are held in position substantially as shown in Figure 1 of the drawings, that is, outspread and lifted from the base 11.

55 It will be noted by reference to Figure

4 of the drawing that the shank 10 is not increased in thickness when viewed from the end of the arms 13, so that the button-hole 15 in the fabric 16 may slip over the ball or head 9, ring 14, and the outspread 60 members of the retainer 12. When the fabric 16 has been seated on the base 11, the feet 13 are raised above the level of the fabric. In this position the button is turned to a position perpendicular to the 65 longest dimension of the buttonhole, or substantially as shown in Figure 3 of the drawings.

The feet 13 now overlay the fabric 16. If the ring 14 be now depressed or moved 70 toward the feet 13, the spreading members are contracted upon the stem 10 as shown in Figure 2 of the drawings, with the result that the feet 13 are depressed upon the fabric 16 to lock the same firmly on the base 75 11. This condition is shown best in Figure 2 of the drawings.

To hold the retainer 12 in the service position shown in Figure 2 of the drawings, is the function of the bumps 17. The 80 bumps 17 are constructed so that the ring 14 can pass thereover to rest in active service therebelow.

It is obvious that when the ring 14 is in the position shown in Figure 2 of the drawings, the bumps 17 hold the ring in service, requiring thereafter some manual effort to lift the ring into the position shown in 85 Figure 1 of the drawings.

It is obvious that when the retainer 12 90 is in the position shown in Figures 2 and 3 of the drawings, the button cannot become separated from the garment or fabric 16. By thus securing the button, many of the disagreeable incidents such as having the 95 button fall from the garment due to an enlargement of the buttonhole, is avoided.

While I have herein described the invention as applied to a collar button, it is obvious that it may be applied to other buttons or devices for uniting in service two portions of a garment where it is desired to remove one portion from the fastening device without releasing the engagement of the fastening device with the other section 105 of the garment.

Claims.

1. A garment button as characterized comprising a base, a head, connecting shank, 110

and a retainer having members spaced apart from said base; and means for closing said members toward said base upon an intervening fabric adapted to clamp the fabric between said members and said base, said means embodying a ring slidably mounted on said shank for contracting the ends of said members upon said shank.

2. A garment button as characterized comprising a base, a head, connecting shank, and a retainer having members spaced apart from said base; means for closing said members toward said base upon an intervening fabric adapted to clamp the fabric between said members and said base, said means embodying a ring slidably mounted on said shank for contracting the ends of said members upon said shank; and means for

holding the said ring in position to contract said members.

3. A garment button as characterized comprising a base, a head, connecting shank, and a retainer having members spaced apart from said base; means for closing said members toward said base upon an intervening fabric adapted to clamp the fabric between said members and said base, said means embodying a ring slidably mounted on said shank for contracting the ends of said members upon said shank; and means for holding the said ring in position to contract said members, said means embodying protuberances on said members in the path of said ring to be over-ridden by said ring.
